UNITED STATES PATENT OFFICE.

HAROLD S. BASSETT AND ARNOLD J. TANNER, OF NORTH HAVEN, CONNECTICUT.

HOLDER FOR METAL TICKETS AND THE LIKE.

1,411,252.

Specification of Letters Patent. Patented Apr. 4, 1922.

Application filed January 31, 1920. Serial No. 355,317.

To all whom it may concern:

Be it known that HAROLD S. BASSETT and ARNOLD J. TANNER, citizens of the United States, and residents of North Haven, in the county of New Haven and State of Connecticut, have invented certain new and useful Improvements in Holders for Metal Tickets and the like, of which the following is a specification.

10 The present invention consists of an improved holder or clip for carrying articles of a class to which metal railway and other tickets, tags, or the like belong; and which articles are desirably kept in a definite order 15 or separated from coins in the pocket, for example. The holder is useful also for the distribution of tickets or the like in quantity because, where used for that purpose, counting, packeting and checking may be dispensed with.

The object of the invention, amongst others, is to provide an efficient holder, simple in construction and easy of operation.

According to the present invention, the 25 holder is composed chiefly or entirely of one piece of wire or metal strip bent so as to form a substantially straight and rigid leg or member on which tickets or the like, having a hole therein, are carried; and another leg or member is provided, the latter being partly parallel with said straight member but having its free end bent so as to be self-bearing upon the straight member, under its own spring tension, thus constantly 35 holding the device closed to keep the tickets on the carrying member. The holder is self opening under action of placing and removing the tickets on and from the carrying member.

40 The two members aforesaid are united by a loop of the wire and in this loop, a plate is suitably mounted and secured. This plate performs several functions, viz., it serves as a convenient handle; it provides a name 45 plate or advertising medium; it reinforces the construction, particularly the carrying member which desirably should be rigid, but the retaining member is left free to move so as to open and close the holder; and further, said plate serves as a stop, preventing 50 the tickets passing around the loop.

Embodiments of the invention are illustrated in the accompanying drawings wherein—

55 Figure 1 is a side elevation of one form of the holder;

Figure 2 is a section taken on line 2—2 looking in the direction indicated by arrow *a*;

Figure 3 illustrates samples of perforated 60 tickets or the like;

Figure 4 is a perspective view illustrating a modified form of the holder especially useful for tickets having an elongated hole, and

Figure 5 is a perspective view showing another modification in which the holder is composed of flattened wire or tapering metal strip whereby the carrying member is made heavier and thus more rigid than the 70 lighter retaining member.

Referring now to the drawings, the device shown in Figure 1 consists of one piece of wire bent to form the straight leg or carrying member 1, which member is connected 75 by the loop 2 with the leg or retaining member 3. The latter member, in part of its length, is substantially parallel with leg 1 and is turned downwardly near its end to form the gradual incline at 4 and then turns 80 upwardly at its extreme end 5. At the bend or offset 5, under constant self spring action, the member 3 bears on the end of the member 1, which latter member, at the point of contact, is flattened so as to better seat 85 the member 3.

The plate 7, secured by ears 8 within the loop 2, besides providing a convenient handle, also gives stability to the device, rendering the member 1 more rigid and 90 tending to prevent the lateral movement of the member 3. The plate 7 also prevents the tickets from passing around the loop and thus being taken off the holder by way of the retaining member. A ring 9 provides 95 means for securing the device to a chain.

The configuration of the tickets 10 may vary, likewise the perforations therein may differ in shape, but still the tickets can be carried on the holder and be conveniently 100 placed thereon and readily taken off. The handle provided, permits the device to be held firmly in a position to facilitate removal of the tickets one or more at one time.

105 In Figure 4 the construction is modified for herein the carrying member is composed of two wires 11, with a closed outer end and the other or inner end being twisted at 12 around the member 3 to give stability 110 thereto and to secure the said member 3 to the loop 2. This form of the holder is par-

ticularly suitable for tickets having an elongated hole therein and possesses the advantages that the carrying member is made more rigid; the tickets are tightly held so that they cannot jingle and the end of the movable or retaining member, when closed, is located between the wires 11, ensuring positively that there can be no lateral or side movement of the retaining member, 10 also, the twist in the wire operates as a stop preventing tickets from sliding therebeyond. Furthermore, the rounded end of the member 1 and globular end 13 of member 3 ensures that the pocket will not be pierced. 15 Various other modifications within the scope of the appended claims may be made, as for example, to provide greater rigidity to the carrying member, the holder may be made entirely of flattened wire or a metal strip as shown in Figure 5, wherein the carrying member is formed of stock heavier than the other part and to provide a stop for the tickets in this instance, the wire or strip is bent at 14 to form a lump or raised 20 portion. 25 In operation, the carrying member is passed through the perforations in the tickets and during this operation the retaining member is raised to open the holder. When taking off a ticket the latter in its movement, raises the retaining member to open the holder, which upon removal of the ticket closes by its own action. The flattened carrying member of the last described modification, it should be noted, serves conveniently as a name plate or the like.

We claim:—

1. A holder for perforated tickets and the like comprising a substantially rigid carrier member capable of receiving and carrying said tickets, a resilient retaining member having its free end bent and adapted to be held in self-locking engagement within an opening or recess provided at the free end of said carrier member, and means located between said members for stopping the passage of the tickets from the carrier member to the retaining member. 40 45

2. A holder for tickets or the like having a handle, a substantially straight and rigid carrying member and a self closing retaining member, all composed of one piece of material, and a reinforcement plate secured to said handle providing a stop for the tickets in one direction of travel. 50 55

3. A self opening and closing holder for perforated tickets, tags and the like comprising a handle; a substantially rigid and straight carrying member; a stop for said tickets or tags limiting inward movement thereof; and a spring member having the free end bearing on the free end of the carrying member and normally closing said holder but self opening under action of placing and taking said tickets or tags on and off said holder. 60 65

Signed at New Haven, in the county of New Haven and State of Connecticut, this 29th day of January, A. D. 1920.

HAROLD S. BASSETT,
ARNOLD J. TANNER.
